UNITED STATES PATENT OFFICE

JOHN Q. SHERMAN, OF DAYTON, OHIO

AUTOGRAPHIC DESK REGISTER

Application filed April 25, 1928. Serial No. 272,754.

My invention relates to autographic registers, and more particularly for registers for use in executive or professional offices for which the ordinary commercial autographic register is inappropriate.

Corporation officials and executives, and professional men as engineers, architects, lawyers and physicians have frequent occasion to make manifold copies of notes, data, references, charges for time or services, and memoranda records of conferences, orders and instruction slips, and the like. The conventional type of autographic register used in industrial and commercial establishments appears quite incongruous in a professional or executive office. Moreover, such professional men or executives ordinarily desire to make such record entries while sitting at their desks. It is inconvenient to operate the ordinary autographic register, while sitting at a desk upon which the register stands. To overcome these difficulties and to provide an installation of an autographic register suitable for professional and executive offices in which the register is normally concealed until time of use, and will then be presented in the most convenient position for making hand written entries, the present construction has been devised.

To this end the autographic register mechanism, whether hand operated or motor driven, is mounted in a desk drawer which may be withdrawn from the desk structure when it is desired to make entries and returns thereto to conceal the register when not in use. The cover of the register mechanism is horizontally disposed substantially flush with the top of the drawer walls. In the event of a hand operated register mechanism a spring retracted operating crank is provided which may be withdrawn beyond the limit of the drawer for easy access. Means is provided for temporarily maintaining the operating crank in such extended position. Upon closure of the drawer containing such autographic register mechanism, the crank holding detent is disengaged and the crank automatically returned incident to the return movement of the drawer. As illustrated in the drawings the register mechanism may

be mounted either in the drawer at the right of the person sitting at the desk in case the register is arranged preferably perpendicular to the desk, or it may be arranged in the center drawer directly in front of the user, in which case it is preferably arranged parallel with the desk.

The object of the invention is to provide an autographic register installation for those surroundings wherein a conventional type of register is inappropriate or objectionable and whereby the register may be normally concealed from view, but wherein the register is readily and easily accessible and is presented in a position convenient to a person sitting at a desk.

A further object of the invention is to provide an improved housing or a cabinet wherein the register mechanism reciprocates into and out of such housing in which it is normally concealed when not in use.

A further object of the invention is to provide actuator means for such register mechanism and means for automatically retracting the actuator means mechanism when the register is returned to its housing.

With the above primary and other incidental objects in view as will more fully appear in the specification, the invention consists of the features of construction, the parts and combinations thereof, and the mode of operation, or their equivalents, as hereinafter described and set forth in the claims.

Referring to the accompanying drawings, wherein is shown the preferred, but obviously not necessarily the only form of embodiment of the invention, Fig. 1 is a perspective view of a portion of a desk in which the register mechanism forming the subject matter hereof has been installed. Fig. 2 is a top plan view of the desk drawer removed from the desk and the cover of the register mechanism removed therefrom. Fig. 3 is a transverse sectional view of the register mechanism coincident with the drive shaft. Fig. 4 is a longitudinal sectional view of the desk drawer with the register mechanism installed therein. Fig. 5 is a detail view of the actuator shaft detent. Fig. 6 is a perspective view of the register mechanism installed in

the center drawer of a desk and in parallel relation with the desk. Fig. 7 is a top plan view of a motor driven register mechanism removed from the desk drawer. Fig. 8 is a detail perspective view of means for clamping the transversely disposed carbon strips.

Like parts are indicated by similar characters of reference throughout the several views.

Referring to the accompanying drawings, 10 1 is a portion of an office desk having therein a reciprocating drawer 2, which forms the cabinet of an autographic register mechanism 3. This register mechanism may be of 15 any suitable form. The register mechanism illustrated has a frame 4 of suitable proportions to be mounted within the drawer 2. The frame 4 supports a writing tablet 5, over which are fed superposed record strips from 20 a supply packet, or roll as the case may be, contained within the drawer 2 and beneath the writing tablet 5. Such record strips pass over guide rollers 6 journaled in the register frame 4, passing thence over the writing 25 tablet 5 and are engaged by revolute pin wheel feeding means engaging in marginal perforations provided in the record strips. The pin wheel feeding device consists of a 30 pair of spaced pin wheels 7 positioned coincident with the series of marginal perforations of the strips. These pin wheels 7 are fixedly interconnected by an intermediate tubular sleeve like portion 8, forming a revolute spool which is journaled in the frame structure 4. This pin wheel spool is rotated by a 35 shaft 9 axially adjustable therein. The shaft 9 carries a hand crank 10. A spring 11 surrounding the actuating shaft 9 within the sleeve 8 of the pin wheel spool tends to retract the shaft, and draw the crank arm 10 within the limits of the drawer 2. The 40 drawer is provided with an opening 12 in one wall thereof, through which the crank arm 10 may be withdrawn for operation of the 45 register mechanism. The withdrawal of the crank arm 10 and actuating shaft 9 to operative position beyond the side wall of the drawer 2 is effected against the tension of the retracting spring 11. When extended to 50 such operative position, a pivoted detent arm 14 pivoted to the inner side of the drawer wall is spring actuated into overlapping relation with a hood 15 upon the shaft 9 as shown in Figs. 3 and 5, thereby holding the shaft and 55 operative crank in extended position against the tension of the retracted spring. The rear arm of the detent lever 14 has a cam projection 16 extending somewhat above the top margins of the walls of the drawer 2. Upon 60 closing movement of the drawer 2, this cam projection 16 engages with the desk structure 1 and is depressed thereby to disengage the detent 14 from the shaft head 15, thus releasing the shaft and crank arm, which are 65 immediately retracted by the reaction of the

spring 11. Overlying the record strips and holding them in engagement with the feeding pins upon the rotating pin wheels is a clamp bar 17 normally held above the paper to permit the free feeding of the strip by cam 70 wheels associated with the pin wheels of the feeding device. These cam wheels permit the clamp bar 17 to be lowered into clamping engagement with the paper at the end of each 75 feeding operation. The construction and operation of this bar 17, which maintains the paper or record strips upon the pins of the feed wheels, and the pin wheel feeding mechanism whereby the bar is kept from clamping contact with the paper during the 80 feeding operation, is illustrated and described in co-pending application for Letters Patent, Serial No. 747,101, filed Oct. 31, 1924. In order that multiple copies of data entered upon the record strip may be made strips of 85 carbon or transfer material are interleaved between the superposed record strips. Such strips of carbon or transfer material are fed transversely across the writing tablet 5 from a supply roller 19, and are received upon a 90 reel shaft 20 at the opposite side of the writing tablet. This reel shaft 20 is rotated manually from time to time by means of a knurled head 21 in order to advance the carbon or transfer material to present a fresh surface 95 in the writing position upon the tablet 5.

Overlying the register mechanism is a cover plate 22 which is positioned approximately level of the top margin of the walls of the drawer 2. This cover plate 22 has therein an opening 23 registering with the writing tablet 5, through which entries may be made upon the uppermost record strip, which entries are transferred to the underlying strips by the intermediate transfer material. The forward end of the opening 23 is depressed below the surface of the cover plate 22 and hinged thereto is a deflector plate 24, by which the upper record strip may be guided from the register to be torn off against the clamping bar 17 110 while the underlying strip is returned to the drawer 2 beneath the register mechanism to afford a duplicate office record.

In Fig. 1 the register mechanism is arranged with the writing tablet extending perpendicular to the desk 1. In this position it may be withdrawn from the desk at the right of the user, where it is quite convenient for making entries through the opening 23 upon the record strip. However, some users may prefer to have the register turned parallel with the desk in which case it may be mounted in the middle drawer of the desk as at 25, in Fig. 6. For illustrative purposes the register shown in Fig. 6 is electrically operated, the 120 motor being controlled by the trip member 27 which serves to interconnect the driving motor with the register feed mechanism. Such construction is shown in detail in Fig. 7, wherein the frame structure 4 is extended laterally 130

to accommodate a driving motor 28. The arrangement of the writing tablet with the pin wheel feeding means for the record strips, the clamp bar operating means, and carbon supply means are the same as before described. Instead of a reciprocatory actuating shaft 9 and crank arm 10 for operating the register mechanism, the shaft in this case is extended laterally as at 29 and is operatively connected with the driving motor 28. A rheostat 30 is connected in the motor supply circuit, and serves to regulate the speed of the motor. The particular motor operated feed devices form no part of the present invention per se, but are fully described and claimed in U. S. Letters Patent 1,437,949 issued Dec. 5, 1922, and also in pending application for Letters Patent Serial No. 24,193, filed April 18, 1925.

In lieu of the revoluble reel shaft for adjusting the transversely extended transfer or carbon sheets the ends of such sheets may be clamped in their adjusted position as shown in Fig. 8. In this modification in lieu of the revoluble reel shaft 20 for receiving the used portion of the transfer paper, such used portion is torn off and the remaining ends of the carbon sheets are secured by means of a spring bar 32 pivotally mounted at 33, and when depressed over the ends of the carbon paper this bar is engageable in a keeper hook 34. In this case the carbon sheets are pulled across the writing tablet by hand to present a fresh surface in writing position and after being securely clamped by pressing the spring bar into the keeper hook the excess used portions of the strips are torn off.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprises the preferred form of several modes of putting the invention into effect, and the invention is therefore claimed in any of its forms or modifications within the legitimate and valid scope of the appended claims.

Having thus described my invention, I claim:

1. The combination with a drawer and a structure in which the drawer is mounted for to and fro reciprocatory motion to alternating closed and open positions, of an autographic register mechanism contained in said drawer, and accessible only when the drawer is open, an actuating shaft for the

register slidingly mounted for axial extension beyond the limit of the drawer, a spring actuated latch arm, one end of which projects above the level of the drawer, a shoulder on the shaft behind which the latch arm engages to hold the shaft when extended, said projecting end of the latch arm being engageable with the mounting structure for the drawer as the drawer is closed to oscillate the latch arm out of engagement with the shaft and permit its return into the drawer.

2. The combination with a drawer and a structure in which the drawer is mounted for to and fro reciprocatory motion, of an autographic register contained therein, a retractable operating device for the register adjustable to a position beyond the limits of the drawer, a detent for temporarily holding the operating means in extended position, means for retracting the operating means when released by said detent and means engaged by said detent upon closing movement of the drawer by which the detent is automatically disengaged to release the operating means.

3. The combination with a drawer, of an autographic register contained within said drawer and a mounting structure in which the drawer is mounted for to and fro reciprocatory motion into which the drawer is retractable to conceal the register from view, and from which the drawer may be withdrawn to an extended position to afford access to the autographic register, the top of the register being substantially flush with the top margin of the drawer walls and actuating means therefor extendable exteriorly of the drawer when open.

4. The combination with a cabinet, and a drawer slidingly mounted therein, of an autographic register mounted within the cabinet drawer and accessible upon withdrawal of the drawer from the cabinet, and means for controlling the operation of the autographic register extensible beyond the limits of the drawer, and means for automatically retracting said control means upon the closing of the drawer.

In testimony whereof, I have hereunto set my hand this 20th day of March, A. D. 1928.

JOHN Q. SHERMAN.
